[57] CLAIM

The ornamental design for a bicycle tire, as shown and
described.

DESCRIPTION

FIG. 1 is a perspective view of a bicycle tire showing
my new design, it being understood that the tread pat-
tern is repeated throughout the circumference of the
tire as shown schematically by solid line, the opposite
side being substantially the same as that shown;
FIG. 2 is a side elevational view thereof;
FIG. 3 is an end elevational view thereof; and
FIG. 4 is an enlarged fragmentary plan view showing
the tread pattern thereof in greater detail.
